UNITED STATES PATENT OFFICE

2,665,421

PROJECTILE LAUNCHING DEVICE

Stanley A. Temple, Rocky River, Ohio

Application February 11, 1950, Serial No. 143,690

8 Claims. (Cl. 1—44.5)

1

This invention relates in general to mechanisms for launching projectiles, and relates more specifically to a device for driving stud pins, rivets and similar members by the force of a combustible material into concrete, steel, or other material for rapid fastening of members together or providing anchoring members.

An object of this invention is to provide a muzzle-loading industrial pin-driving gun.

Another object of this invention is to provide a selectable resistance to movement of a projectile out of the gun in order to build up a force of suitable intensity for the desired driving force before the projectile is launched.

Another object of this invention is to provide a projectile launching device which may be fired by pressing the device against the surface to be penetrated.

Still another object of this invention is to provide a projectile launching device having a positive manually operated safety lock and a firing lock operated by a trigger extending beyond the end of the gun barrel in order that the device may not be fired accidentally or purposely until the manual lock is first opened, and the firing lock is operated by pressing the device against the work to be penetrated.

Other objects and a fuller understanding of the invention may be had by referring to the following description and claims, taken in conjunction with the accompanying drawing, in which:

Figure 1 is a longitudinal section of the preferred embodiment of the invention showing the firing mechanism and sleeve trigger extended in their relaxed position;

Figure 1A is a view taken along line 1A of Figure 1;

Figure 1B is taken along line 1B of Figure 1;

Figure 2 is the same sectional view illustrating the method of cocking the firing mechanism;

Figure 2A is a perspective view of the cocking of a cocking tool which is useful in cocking the firing mechanism of the invention;

Figure 3 is the same sectional view as Figure 2 showing the top half only of the tool, and illustrating the firing mechanism locked in cocked position by a manually operated collet lock;

Figure 4 illustrates the effect of extending the trigger sleeve after the collet lock is tightened to extend the stud pin lock into engagement with the firing mechanism;

Figure 5 illustrates the fully loaded tool with a combustion-propellable projectile gripped in the breach-loading bore, and with both lock devices in full engagement with the firing mechanism;

2

Figure 6 is a sectional view illustrating the step of releasing the manual collet lock preparatory to firing the tool; and

Figure 7 is a perspective exploded view of the preferred type of combustion-propelled projectile.

In the drawings, the preferred embodiment of the invention is illustrated in longitudinal section. The preferred embodiment comprises a substantially cylindrical construction in all parts, and therefore a longitudinal section is believed to be all that is necessary to completely set forth this preferred embodiment.

In Figure 1 of the drawings the preferred embodiment is illustrated as comprising a gun body 10 having a sleeve trigger 11 reciprocably bearinged thereon for longitudinal telescoping and retracting movement. A safety tube housing 12, although not essential to the operation of the tool, is employed to encase the gun body and sleeve trigger. The gun body 10, it will be understood, may be made in several different ways, but the illustrated form has been designed for manufacturing convenience and has been built and successfully operated. Accordingly, this method of construction is set forth to illustrate the principles of the invention with the understanding that they can be modified according to particular requirements of manufacture. The gun body is composed of a core 13 with a barrel chamber insert 14 therein. A barrel nose 15 is threadably secured upon the end of the core 13 and holds the barrel chamber insert 14 securely within the core 13. Both the barrel chamber insert 14 and the barrel nose 15 are provided with an axial bore of identical diameter which become longitudinally extensive with respect to one another and define a bore 16 to guide a projectile from the gun body 10.

The portion of the bore 16 in the barrel nose 15 constitutes the muzzle end of the gun body 10.

A passageway opening 17 of reduced diameter with respect to the bore 16 extends longitudinally from the bore 16 along a common axis therewith and interconnects the bore 16 with a firing pin chamber 18. The bore 16, passageway 17, and firing pin chamber 18 are all axially aligned and interconnected throughout the length of the gun body 10.

A firing pin 19 having an enlarged head portion 20 is longitudinally reciprocable within the firing pin chamber 18 and the passageway 17. The firing pin, when in the position illustrated in Figure 1, will just extend into the bore 16, in an area of the bore 16 defined as the combustion

chamber portion 62. A plunger 21 having a stem portion 24 is mounted within the firing pin chamber 18 for longitudinal reciprocable movement and is urged toward the muzzle end of the gun body 10 by a spring 22. The two-piece firing pin means, having the firing pin 19 floating free without a bias force, together with the spring-loaded plunger 21, has proven to be desirable, although not essential, because the plunger 21 acts as a hammer striking an anvil, thereby giving the firing pin a shock blow rather than a steady pressure. It has been found that a shock blow will result in a more certain detonation than a steady pressure. In the illustrated embodiment, the enlarged head portion 20 fits very close to the chamber 18, and therefore when the stem of the pin enters the passageway 17, acts as a dashpot to prevent free movement of the firing pin when the plunger 21 is cocked. Thus, the firing pin 19 will move slowly, although it is not mechanically restrained, and will not accidentally detonate a sensitive charge before the plunger 21 is released.

A collet chuck 25 is threadably secured at the upper end of the chamber 18. A collet 26 is carried within the chuck 25 and is longitudinally shiftable with respect to the chuck by means of a handwheel or nut 27 to thereby close the collet by cam action engagement with the chuck. The stem portion 24 of the plunger 21 is longitudinally reciprocable within the collet 26 and may therefore be gripped and held in a stationary position by tightening the collet 26. The operation of the collet and collet chuck is well known and is believed to be unnecessary to further set forth the operation to explain its principles. A thrust washer 28 is provided at the end of the collet 26 to serve as a bearing surface for the end of the spring 22. For convenience of reference the entire collet mechanism will hereinafter be referred to as the manual collet lock 23. This lock 23 is termed a manual lock because it is operated to grasp or release the stem portion 24 only upon manual rotation of the handwheel 27, and not by the mechanical operation of another part to release the collet lock 23.

A retainer ring 30 is positioned at the end of the housing safety tube 12 and encompasses the top of the core 13. A set screw 31 is provided to hold the retainer ring in the illustrated position. A spring 32 extends between the retainer ring 30 and the top of the trigger sleeve 11 and thereby tends to urge the trigger sleeve 11 to a longitudinally extended position with respect to the gun body 10. A stop sleeve 33 closely encompasses the core 13 under the spring 32 and limits the distance which the trigger sleeve 11 can be retracted against the urge of the spring 32.

A longitudinal slot 34 is provided in the side of the trigger sleeve 11, and a guide screw 35 is threadably engaged into the core 13 to provide a guide surface engaged within the slot 34 and hold the trigger sleeve 11 against a spiraling motion as the trigger sleeve 11 reciprocates with respect to the gun body 10.

A second slot 36 has been provided on the trigger sleeve, and this second slot 36 is provided with rack gear teeth on one side wall thereof. A threaded stud 37 is engaged in a threaded opening 38 extending through the wall of the core 13 and opening into the firing pin chamber 18. The threaded stud 37 has a pinion gear head 42 adapted to mesh with the rack gear teeth on the wall of the slot 36, and therefore as the trigger sleeve 11 is reciprocated in a telescoping and retracting direction with respect to the gun

body 10, the threaded stud 37 will be advanced and retracted with respect to the firing pin chamber 18. A bearing screw 41 is carried by the housing safety tube 12 and has a pin portion which serves as a bearing to aid in supporting the threaded stud 37 when the stud 37 is retracted with respect to the opening 38. The slots 34 and 36 may be combined to serve both functions, if desired.

The plunger 21 is formed with a lock-engaging surface 39 thereon, and in the illustrated embodiment this lock-engaging surface 39 comprises an annular groove. The threaded stud 37 has a tip 40 thereon to extend into the lock-engaging surface 39 provided by the annular groove. Therefore, it will readily be seen that upon alignment of the lock-engaging surface 39 with the tip 40, the tip 40 may be advanced by extending the trigger sleeve 11 and therefore interfere with the movement of the plunger 21.

In order to cock this projectile launching device a cocking tool 45 is provided. The tool 45 has a base 46 and a pin 47. The pin 47 is inserted into the bore 16 and the entire launching device 25 is pressed forward against the base 46. The trigger sleeve 11 is pressed against the base 46 and therefore is retracted against the urge of the spring 32. Such retraction of the trigger sleeve 11 will rotate the threaded stud 37 by means of the pinion gear head 42 and the rack threaded slot 36 to a retracted position, withdrawing the tip 40 out of the firing pin chamber 18, compare Figures 1 and 2. Simultaneously with the retraction of the trigger sleeve 11, the pin 47 of the cocking tool will pass through the passageway 17 and press the firing pin 19 against the urge of the spring 22. The length of the pin 47 is such that the plunger 21 will exactly position the lock-engaging surface 39 on the plunger 21 in the fixed path traveled by the threaded stud 37. Therefore, because the movement of the trigger sleeve 11 in a retracting direction is limited by the stop sleeve 33, and the retracting movement of the firing pin means is exactly controlled by the length of the pin 47, a perfect alignment of the lock-engaging surface 39 with the fixed longitudinal path of travel for the threaded stud 37 is automatically determined by simply pressing the projectile firing device against the cocking tool 45. The cocked position, with the cocking tool 45 in place, is illustrated best in the Figure 2 of the drawings.

After the firing pin means and the trigger sleeve 11 have been moved to the position illustrated in Figure 2 of the drawings, the manual collet lock 23 may be tightened as illustrated in Figure 3 to grip the stem portion 24 of the plunger 21. The collet 26 grips the stem 24 at a grip point illustrated by the reference character 48.

After the stem 24 has been gripped by the manual collet lock 23 the cocking tool 45 and the projectile launching device can be separated, thereby allowing the sleeve trigger 11 to telescope 65 beyond the end of the gun body 10 under the urge of the spring 32 (see Figure 4). When the trigger sleeve 11 moves to the forward position under the urge of the spring 32 the threaded stud 37 will rotate as previously described and 70 advance the tip 40 into the firing pin chamber 18. The lock-engaging surface 39 on the plunger 21, having been previously positioned in line with the fixed path of travel of the tip 40, and held in that position by the manual collet lock 23, the tip 40 will engage into the lock-engaging surface 75

39 and therefore interfere with movement of the plunger 21 (see Figure 5). Accordingly, even though the collet lock 23 is released, the mechanically operated lock provided by the threaded stud 37 will not permit movement of the plunger 21 (see Figure 6).

An advantage of the illustrated embodiment of the tool lies in the ability to muzzle-load a projectile into the bore 16 rather than having to have a method of breaking down the tool and insert a breech-loaded shell. In Figure 7 of the drawings a combustion projectile 50 is illustrated in exploded perspective. The term "combustion projectile" is used to mean an actual projectile piece such as a projectile 51 having associated therewith a rapidly burning material which will form a driving force when confined to a limited area. Normally a combination of projectile and combustion material, as used in firearms and prior devices intended for the same purpose as this invention, employ a shell having a flanged cap to hold the shell from moving through the barrel of the gun. In this invention, although such a construction is feasible for use with the other features of the invention, it has been found to be a distinct advantage to provide the combustion projectile 50 in which the rapidly combustible material is held in close proximity to the actual projectile 51, such as by cementing, without being encased in any type of temporary holding shell. In Figure 7 the projectile 51 has a threaded neck portion 52 with a removable collar 53 threaded thereon. The collar 53 is dimensioned to closely fit within the combustion chamber portion 62 of the bore 16. A capsule of combustible material is indicated by the reference character 54. Any suitable rapidly burning combustible material may be employed for the propellant material, but it has been found that a rapid burning fuse material will serve the purpose very well. The capsule 54 has a longitudinal hole 55 therethrough which will conveniently hold an ignition cap 56 of well-known structure quite widely used with explosive materials.

The combustion projectile, that is, the completely assembled projectile including the rapidly combustible material, is inserted into the muzzle end of the bore 16 and moved by gravity into the combustion chamber portion 62. A pressure screw 58 is threadably engaged into a threaded opening 60 passing through the side wall of the core 13 and opening into the combustion chamber portion 62. A longitudinal slot 57 is provided in the trigger sleeve 11 in order to allow the trigger sleeve to reciprocate without interference from the pressure screw 58, and an opening 59 is provided through the housing 12.

After the combustion projectile 50 reaches the upper end the combustion chamber 62, the pressure screw 58 may be tightened down to engage the threaded collar 53 and clamp the combustion projectile 50 in the bore 16 with any desired degree of tightness. This embodiment of the invention offers the distinct advantage of being able to place a selected resistance to movement of the projectile out of the bore 16 and therefore preselect the muzzle velocity of the projectile. In using ordinary shell type of projectiles the resistance to movement of the projectile from the launching device is determined by the friction between the projectile and the shell. According to this invention each combustion projectile 50 can be controlled as to muzzle velocity by the degree to which the pressure screw 58 has been tightened.

The Figure 5 of the drawings illustrates the projectile launching device of this invention fully loaded with both the manual collet lock 23 and the mechanical lock provided by the threaded stud 37 in full engagement with the firing pin means in order to prevent discharge of the projectile. In order to prepare the launching device for use, the manual collet lock 23 is released and the launching device then appears as illustrated in Figure 6 of the drawings. To fire the projectile 51 from the bore 16 after the manual collet lock 23 has been released, the entire launching device is pressed against the surface intended to be penetrated by the projectile 51 to retract the trigger sleeve 11 with respect to the gun body 10. Such retraction as previously explained, will cause the threaded stud 37 to rotate and withdraw from the firing pin chamber 18, thereby disengaging the lock-engaging surface 39 on the plunger 21 and permitting the spring 22 to drive the firing pin 19 into the combustion chamber 62 and fire the combustible material to drive the projectile 51 from the bore 16.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A projectile launching device comprising, a gun barrel, a sleeve mounted on said gun barrel for relative telescoping movement between extended and contracted relative positions, said gun barrel having a bore with a combustion chamber portion to hold a firable combustion-actuated projectile, spring urged firing pin means including a firing pin point extendable into said combustion chamber portion, first lock means to hold said firing pin means inactive against the urge of the spring, control means for said first lock means operable by relative movement of said sleeve and said gun barrel from said extended to said contracted relative positions to release said first lock means, and second lock means manually operated to hold said firing pin means inactive against the urge of the spring to prevent unintentional activation of the firing pin means by the control means.

2. A projectile launching device comprising, a gun barrel, a sleeve mounted on said gun barrel for relative telescoping movement between extended and contracted relative positions, said gun barrel having a bore, means to hold a firable combustion-actuated projectile in said bore, a spring urged firing pin including a firing pin point extendable into said combustion chamber portion, said firing pin having a stem portion, first lock means to hold said firing pin means inactive against the urge of the spring, control means for said first lock means operable by relative movement of said sleeve and said gun barrel from said extended to said contracted relative positions to release said lock means, and second lock means manually operated to hold said firing pin means inactive against the urge of the spring, said second lock means including a collet to grip said stem portion to prevent unintentional activation of the firing pin means by the control means.

3. A projectile launching device comprising, a longitudinal gun barrel having a muzzle end,

said gun barrel having a bore therein opening at said muzzle end, means to hold a projectile in said bore, firing means operable to fire a combustion-actuated projectile held within said bore, a trigger sleeve, said gun barrel extending within the sleeve, yieldable means urging said sleeve and gun barrel to an extended position with the sleeve extended beyond the muzzle end of said gun barrel in a first relative position, said sleeve and gun barrel being relatively retractable against the urge of said yieldable means to a second position wherein the sleeve is positioned rearwardly of said first position relative to said gun barrel, and implementation means driven by mechanical drive means interconnected between said gun barrel and trigger sleeve implementing the firing means upon relative movement of the gun body and the trigger sleeve to said second position.

4. A projectile launching device comprising, a longitudinal gun barrel having a muzzle end, said gun barrel having a bore therein opening at said muzzle end, a threaded opening extending at an angle to said bore through said barrel into said bore, screw means engaged in said threaded opening to clamp a projectile in said bore with a selectable degree of tightness, a trigger sleeve member, said gun barrel extending within the sleeve member, said sleeve member and gun barrel being relatively reciprocable from a first relative position wherein the sleeve is extending beyond said muzzle end of the gun barrel to a second relative position wherein the sleeve is retracted from said first position rearwardly relative to said gun barrel, an entry opening into said bore for a firing pin, said firing pin dimensioned to extend through said entry opening into said bore to the position therein occupied by a loaded projectile, said firing pin mounted for reciprocable movement through said opening, biasing means urging said firing pin to project through said entry opening into said bore, lock means for holding said firing pin inactive against the urge of said biasing means, and implementation means driven by mechanical drive means interconnected between said gun barrel and trigger sleeve implementing the firing means upon movement of the gun barrel and sleeve to said second relative position.

5. A projectile launching device comprising, a longitudinal barrel having a muzzle end, said gun barrel having a bore therein opening at said muzzle end, grip means to hold a projectile in said bore, a trigger sleeve member, said gun barrel extending within the sleeve member, said sleeve member and gun barrel being relatively reciprocable between a first relative position wherein the sleeve is extending beyond said muzzle end of the gun barrel and a second relative position wherein the sleeve is retracted from said first position rearwardly relative to said gun barrel, an entry opening into said bore, a firing pin dimensioned to extend through said entry opening into said bore to the position therein occupied by a loaded projectile, said firing pin mounted for reciprocable movement through said opening, biasing means urging said firing pin to move along a firing path and drive said firing pin into said bore, interference lock means carried by said barrel, said interference lock means having a lock condition interfering with movement of the firing pin along said firing path, and having an unlocked condition not interfering therewith, and mechanical drive means for said interference lock means interconnected between said trigger sleeve member and the gun barrel,

said drive means setting up said lock condition of the lock means when the trigger sleeve and gun barrel are moved relative to one another to said first position, and setting up said unlocked condition when the trigger sleeve and gun barrel are moved relative to one another to said second position.

5 6. A projectile launching device comprising a longitudinal barrel having a muzzle end, said gun barrel having a bore therein opening at said muzzle end, a sleeve mounted on said gun barrel, said barrel extending within the sleeve, means to hold a firable projectile within said bore rearwardly of said muzzle end of the barrel, manually cockable spring loaded firing means disposed to contact a firable projectile loaded in said bore, said firing means having a defined path of movement to fire a projectile, threaded stud guide means with a stud threadably engaged therein, 10 said threaded stud guide means defining a longitudinal path of travel for said stud, said path of travel for the stud extending across the said defined path of movement of the firing means, stud rotation drive means operable by relative 15 telescoping movement of said barrel and sleeve, relative advance movement of the sleeve with respect to the gun barrel to a position wherein the sleeve extends beyond the muzzle of the barrel providing rotating of the stud in the guide 20 surfaces in a direction advancing the stud into the said defined path of movement of the firing means to thereby block movement of the firing means, and retracting movement of the sleeve and said barrel retracting said stud out of said 25 defined path.

7. A projectile launching device comprising a longitudinal barrel having a muzzle end, said gun barrel having a bore therein opening at said muzzle end, a sleeve carried in telescoping reciprocable arrangement with respect to said barrel for movement of the sleeve from a position where the end of said sleeve extends beyond the end of said barrel to a position in a plane substantially flush with the end face of said barrel, means to hold a firable projectile within said bore rearwardly of said muzzle end of the barrel, spring urged firing means disposed to contact a firable projectile loaded in said bore, said firing means having a defined path in which it can be moved to fire a projectile, threaded stud 40 guide means with a stud threadably engaged therein, said threaded stud guide means defining a longitudinal path of travel for the said stud, said path of travel for the stud extending across the said defined path of movement of the firing means, said stud having a pinion toothed drive portion, rack teeth carried by said sleeve in driving engagement with the pinion toothed drive 45 portion of the stud, said rack teeth being longitudinally reciprocable by extension and retraction movements of the sleeve and the gun barrel relative to one another, said threaded stud guide means and stud being formed to advance said stud into said defined path of movement of the 50 firing means upon rotation of said stud as relative movement of the barrel and sleeve takes place to position the sleeve beyond the muzzle end of the gun barrel to thereby block movement of the firing means, and relative retracting movement of the sleeve and gun barrel retracting said stud out of said defined path of movement, and 55 manual lock means carried by said barrel and operable to hold said firing means in an inactive position after being cocked against the urge of said spring, said stud and said firing means hav- 60

70 75

ing mutually interlockable surfaces which are aligned longitudinally of said stud only when the firing means is cocked and are interengaged by the said advance movement of the stud.

8. A projectile launching device comprising, a 5 relatively reciprocable telescoping gun barrel and sleeve, spring means urging said sleeve and barrel to move to a relative position wherein the sleeve is extending beyond the end of said gun barrel, said sleeve and gun barrel being relatively movable to a retracted position, said gun barrel having a muzzle-loading bore, and means at said muzzle end for receiving a cocking tool, means positioned to engage and clamp a firable projectile in said bore, a firing pin chamber extending axially aligned with said bore, a passageway from said firing pin chamber to said bore, firing pin means in said firing pin chamber including a firing pin point dimensioned to pass through said passageway into said bore, spring 20 means mounted to urge said firing pin point into a firing position extending into said bore, said firing pin means being retractable from said firing position to a cocked position by manually forcing said firing pin means against the spring 25 with said cocking tool, said barrel having a laterally extending threaded opening through to said firing pin chamber, a threaded lock stud threadably engaged in said threaded opening, said firing pin means and said stud having mutually interlockable surfaces, said interlockable 30

surfaces of the firing pin means and lock stud being aligned in said cocked position, said stud having a pinion gear head, longitudinally extending rack teeth carried by said sleeve engaged with said pinion gear head, the threaded opening and rack teeth being formed to rotate said stud and advance said stud into said firing pin chamber to a lock position upon movement of the sleeve and rack thereon to said advanced position, retraction movement of said sleeve and rack relative to said barrel thereby retracting said stud out of said firing pin chamber to an unlocked position, said firing pin means having a stem portion, and a manually operable collet carried by said barrel and positioned to receive and grip said stem portion.

STANLEY A. TEMPLE.
